UNITED STATES PATENT OFFICE.

ARTHUR W. WELLINGTON AND ARTHUR F. RYAN, OF SAN JOSE, CALIFORNIA.

CENTRIFUGAL PUMP.

1,386,293.

Specification of Letters Patent.

Patented Aug. 2, 1921.

Application filed November 1, 1920. Serial No. 421,088.

To all whom it may concern:

Be it known that we, ARTHUR W. WELLINGTON and ARTHUR F. RYAN, citizens of the United States, and residents of San Jose, in the county of Santa Clara and State of California, have invented certain new and useful Improvements in Centrifugal Pumps, of which the following is a specification.

10 Our invention relates particularly to the operating mechanism of a deep well centrifugal pump. It is the object of our invention to provide an operating mechanism of the character indicated in which the usual 15 bearings for the driving shaft are entirely eliminated between the pump and the pump bowl, thereby materially simplifying the construction and reducing the cost of producing and installing the type of pump referred, as well as materially reducing the 20 cost of operation and upkeep of the pump.

In the drawing:

Figure 1 is a vertical section through a deep well equipped with a pump embodying 25 our invention.

Fig. 2 is an enlarged detail section through a form of pump head that may be used in a pump embodying our invention.

Fig. 3 is an enlarged detail section through 30 a form of pump bowl that may be used in a pump embodying our invention.

Fig. 4 is a plan view of the structure shown in Fig. 2.

Fig. 5 is an enlarged detail section through 35 a type of shaft coupling adapted for use in our invention.

Referring more particularly to the drawings, 1 indicates a well in which a pump bowl 2 is suspended by means of discharge 40 casing column 3 provided with a discharge opening at 4 and a pump head at 5. In the present instance the pump head 5 is shown as threaded at 6 to receive a bearing 7 for pump shaft 8, the bearing 7 having a race- 45 way 9 formed therein for ball bearing 10, and the shaft 8 having a collar 11 secured thereto and provided with a raceway 12 to engage ball bearing 10. On bearing 7 is formed a flange 13 having an hexagonal outer surface as 14 to permit the application 50 of an instrument thereto for turning bearing 7 in head 5. Flange 13 also forms a basin 15 for a quantity of oil for lubricating the bearings.

55 Bowl 2 is of the well known type having a bearing supported therein as at 16, the

shaft 8 carrying the usual impeller 17. In the present case the bearing 16 is provided with a raceway 18 to receive ball bearings 19, and impeller 17 is provided with a raceway 20 to receive said ball bearings 19. The shaft 8 is built up of the necessary number of lengths of shaft sections joined by couplings 21 and is unsupported in any way between the top bearing 7 and the bearing 16 in the pump bowl.

When a pump of this type is in operation the thrust of the impeller and the weight of the water thereon places shaft 8 under considerable tension. Also the dead weight of 70 the moving parts themselves exerts a tensional stress upon the shaft 8. This ordinary tensioning of shaft 8 we have found tends to eliminate vibration and swaying thereof, and this tendency to vibrationless 75 running of the shaft is greatly augmented by the equal pressure of the water itself upon all sides of the shaft. We have further found that the vibrating of the shaft is greatly reduced if a shaft of small diameter 80 is used instead of the ordinary steel shafting of comparatively large diameter. In other words, the less the cross-sectional area of the shaft used the less the vibration or swaying of the shaft. The shaft must, of 85 course, have the necessary strength to remain intact under the high torsional strain to which it is subjected. We have found, in practice, that a high grade chrome steel alloy shaft of small diameter gives excellent 90 results. We have also found that a shaft of this character is somewhat flexible and a shaft having some flexibility is more easily rendered vibrationless by the direct water pressure and tensional strains thereon than 95 a shaft of more rigid construction. In fact a perfectly flexible shaft would be preferable to a more or less rigid one because a swaying movement set up in any portion thereof is more local in its nature and is 100 more rapidly overcome by the tensional strain on the shaft, but a perfectly flexible shaft, such as a cable, is materially shortened in length by the twisting thereof and therefore a shaft of the character indicated is 105 deemed preferable. While a cold rolled steel shaft of the usual type is not desirable in the present invention for comparatively shallow wells, its fitness increases proportionately as the depth of the well, it being 110 obvious that a long steel shaft is more flexible than a short one.

The tensioning of shaft 8 may be increased by inserting roller bearings in the head as at 10 and bearings in the bowl as at 19, and providing a means for tightening the shaft between the two bearings as by the adjustment of threaded member 7. It is apparent that where bearings as shown at 10 and 19 are used the discharge casing column 3 acts as a compression member, but the bearing 19 may not always be required in which case casing 3 functions only in its customary manner.

The water pressure in discharge casing column 3 may be further utilized by forming the couplings 21 as shown in Fig. 5 with a cone shaped surface 22. Since the water moves more or less rapidly upward past the coupling, the latter at the same time being rapidly revolved, an angular upward thrust against the coupling is effected which tends to steady the shaft and hold it in its vertical position.

It is clear, of course, that many modifications of the invention herein disclosed may be made, the present disclosure being illustrative of the invention only, and that changes in form, construction and method of operation may be made within the scope of the appended claims.

30 We claim:

1. A pump mechanism comprising a pump head, a discharge casing column suspended therebelow, a pump bowl supported by said

discharge casing column, an impeller arranged in said bowl, and a flexible driving shaft operatively mounted with relation to said head and said impeller and unsupported against a swinging movement with respect to its normal vertical axis between said head and bowl. 40

2. A pump mechanism comprising a pump head, a discharge casing column suspended therebelow, a pump bowl supported by said discharge casing column, an impeller arranged in said bowl, a driving shaft operatively mounted with relation to said head and said impeller, and unsupported against a swinging movement with respect to its normal vertical axis between said head and bowl, and means for tensioning said shaft 50 between said head and bowl. 45

3. A pump mechanism comprising a pump head, a discharge casing column suspended therebelow, a pump bowl supported by said discharge casing column, an impeller arranged in said bowl, a driving shaft operatively mounted with relation to said head and said impeller, and unsupported by bearings between said head and bowl, and means mounted on said shaft to coöperate with the 60 moving water in said casing column for steading the movement of said shaft when revolving. 55
